Primary Examiner — Leanne Was-Englehart

Assistant Examiner — Alison Davis

(57) **CLAIM**

The ornamental design for a mobile smart tablet with stand, as shown and described.

DESCRIPTION

FIG. 1 is a front, right and top perspective view of a mobile smart tablet with stand showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 in FIG. 1;

FIG. 10 is an enlarged view of area 10 in FIG. 2;

FIG. 11 is an enlarged view of area 11 in FIG. 2;

FIG. 12 is an enlarged view of area 12 in FIG. 2;

FIG. 13 is an enlarged view of area 13 in FIG. 2; and,

FIG. 14 is an enlarged view of area 14 in FIG. 4.

The broken lines in the figures illustrate portions of the mobile smart tablet with stand that form no part of the claimed design. The dot-dash broken lines represent boundaries of the enlarged portions and form no part of the claimed design.

1 Claim, 14 Drawing Sheets
